UNITED STATES PATENT OFFICE.

THOMAS J. WILLIAMS, OF COALWOOD, WEST VIRGINIA.

COAL-TIPPLE.

1,212,723.

Specification of Letters Patent. Patented Jan. 16, 1917.

Application filed November 16, 1915. Serial No. 61,803.

To all whom it may concern:

Be it known that I, THOMAS J. WILLIAMS, a citizen of the United States, residing at Coalwood, in the county of McDowell and State of West Virginia, have invented certain new and useful Improvements in Coal-Tipples, of which the following is a specification.

This invention contemplates an improved 10 coal tipple and has as its primary object to provide a device of this character so constructed that cars having solid bodies without seams or end gates, may be employed in connection therewith so that the loss of slack 15 coal along the mine tracks when the cars are in motion, will be eliminated.

The invention has as a further object, in this connection, to eliminate the scattering of dust along the mine tracks which, in bituminous mines generating explosive gas, directly contributes to many mine disasters.

A still further object of the invention is to provide an improved tipple having an exceedingly high capacity with a minimum 25 breakage of coal and wherein the tipple will be automatic in its operation to dump the loaded cars thereon as the cars are advanced from the mine tracks to position upon the tipple.

Other and incidental objects will appear as the description proceeds and in the drawings wherein I have illustrated the preferred embodiment of the invention and wherein similar reference characters designate corresponding parts throughout the several views. Figure 1 is an end elevation of my improved tipple showing the mounting of the dumping element thereof as well as the manner in which the cars are held in position upon the 40 platforms of the said element. Fig. 2 is a fragmentary plan view particularly showing the automatic stop mechanism associated with the tipple as well as the automatic stop mechanism carried by each platform of the tipple. Fig. 3 is a fragmentary longitudinal sectional view taken on the line 3—3 of Fig. 2 and particularly showing the mounting of the stop mechanism carried by the platforms of the tipple. Fig. 4 is a fragmentary front elevation more particularly showing the manner in which the stop mechanism for the tipple is adapted to cooperate therewith, and Fig. 5 is a fragmentary perspective view of one of the bumpers associated with the stop mechanism carried by each platform of the tipple as well as the

pivotal connection between the said bumper and the operating link therefor.

In carrying out my invention, I employ a rotary dumping element including spaced 60 annular members 10, the outer faces of which are channeled. Rotatably supporting the members 10 upon a shaft 11 are a plurality of spokes 12 and the said shaft is journaled for rotation in suitable bearings conventionally shown at 13, one of the said bearings being arranged at each end of the said element. Extending between corresponding spokes of the elements 10 are cross pieces 14 which define a plurality of platforms and mounted 70 upon each of said platforms are rails 16 which provide a track adapted to receive a coal car. Preferably, the dumping element is provided with six of the platforms as more particularly shown in Fig. 1, each identical in construction and for the purposes of illustration, I have shown a coal car upon four of the said platforms and numbered respectively 17, 18, 19 and 20. The dumping element may be of any desired diameter and 75 length and mounted beneath the said element to extend laterally therefrom, is a chute 21 adapted to receive the coal as it is dumped from the cars and preferably of a width to extend throughout the distance between the 80 members 10 of the dumping element, as more particularly shown in Fig. 4. Associated with each of the platforms are pairs of coacting brackets arranged at opposite sides of the rails thereof, the brackets of each pair 85 being numbered 22 and 23 respectively. Preferably, these brackets extend throughout the entire length of the platforms and the brackets 22 are adapted to engage over the wheels of a car while the brackets 23 are 90 adapted to coact with brackets 24 carried by the sides of the car, as more particularly shown in Fig. 1. As illustrated in this figure, these brackets will, when the cars are moved to position upon the tipple, hold the 95 said cars firmly upon the platforms thereof.

Mounted upon each of the platforms of the dumping element is an automatic stop mechanism for the cars, as particularly shown in Figs. 2 and 3 of the drawings. 105 As the stop mechanism for each platform is identical, reference will now be made to a single platform. Referring more particularly to these Figs. 2 and 3, it will be noted that this stop mechanism includes longitudinally disposed rock shafts 25 arranged adjacent the rails 16 and each mounted for

longitudinal sliding movement in a pair of spaced clips 26 carried by a plate 27 extending transversely between the rails and secured to the spokes 12 of the dumping element at the ends of the platform and to the adjacent cross piece 14. The inner extremities of the rock shafts are headed and bearing between the said heads and the innermost of the clips 26, are helical springs 28 surrounding the shafts. Keyed or otherwise connected to the shafts 25 and arranged between the clips 26 are bumpers 29 one of which is shown in detail in Fig. 5. These bumpers are provided with longitudinally curved arms 30 extending laterally therefrom beneath the rails and freely received within suitable slots 31 formed therein with the upper ends of the said arms projecting into the path of the wheels of a car moving over the rails. As will be noted, the forward edges of the said arms are cut away to receive the car wheels. The bumpers 29 are formed with upstanding ears 32 which freely receive rock pins 33 and pivotally connected to the rock pins are links 34, the outer ends of which are preferably bifurcated to receive the pins 33 and are secured thereto by a bolt or other suitable fastening device.

30 The inner extremities of the links 34 are pivotally connected to a rod 35 extending longitudinally between the rails and supported for longitudinal shifting movement by spaced clips 36 and 37 respectively. The bumpers 29 are arranged at any convenient location adjacent the discharge end of the platform and mounted upon the platform adjacent its receiving end is a trip lever 38 extending upwardly between the rails of the platform 40 and pivotally connected to the adjacent extremity of the rod 35. Pivotally supporting the trip lever 38 are suitable brackets 39 secured to the plate 27. It will now be observed that a car entering upon the platform will pass over the trip 38 to depress the trip which will accordingly shift the rod 35 longitudinally and move the links 34 to a position in alignment with each other. The links will, in turn, accordingly rock the shafts 25 and throw the arms 30 of the bumpers 29 outwardly in opposite directions away from the rails so that a car may pass from the platform. For returning the arms of the bumpers to normal position, within 55 the slots 31 of the rails, I employ a helical spring 40 which surrounds the rod 35 and is arranged to bear between a suitable collar 41 preferably mounted upon the rod and a stop 42 associated with the rod and engaging the clip 37, the said spring acting to normally urge the links 34 to the position shown in Fig. 2.

Arranged to coöperate with the rotary dumping element, is an automatic stop mechanism, the mounting of which is more

particularly shown in Figs. 2 and 4 of the drawings. A track 43 leads from the discharge end of the dumping element and associated with this track at a suitable distance beyond the discharge end of the dumping element is a rock shaft 44 arranged transversely of the track to extend laterally therefrom upon one side of the dumping element. Projecting upwardly from this shaft 44 between the rails of the track 43 is a trip lever 45 and the said shaft adjacent the outer end thereof is also provided with longitudinally spaced upstanding arms 46 and 47 respectively, arranged upon the outer side of the track 43. Mounted adjacent the receiving end of the dumping element with which is associated a track 48, is a rock shaft 49 arranged upon the outer side of the said track and provided with diametric arms 50 and 51 respectively, the arm 51 being shown in dotted lines in Fig. 4. Connecting the arm 50 with the arm 47 of the shaft 44 is a rod 52 and associated with the said rod is a stop sleeve 53. Bearing between the said sleeve and a suitable collar carried by the rod is a helical spring 54 which surrounds the rod.

Arranged to project into the path of the spokes of the members 10 of the dumping element, are stops 55 and 56 respectively which are slidably mounted within suitable sleeves 57 and are arranged to engage the said spokes 12 of the dumping element adjacent the outer ends thereof. Connecting the stop 55 with the arm 51 of the shaft 49 is a link 58 while a similar link 59 connects the stop 56 with the arm 46 of the shaft 44. It will now be noted that when the lever 45 is engaged by a car passing along the track 43 from the dumping element, the said lever will rock the shaft 44 and the stops 55 and 56 will be withdrawn to release the dumping element for rotary movement. Immediately upon the release of the lever 45 by the car, the spring 54 acting upon the sleeve 53 and the collar carried by the rod 52, will return the stops to normal position in the path of the spokes of the dumping element. In this connection it is pointed out that the lever 45 is arranged at such distance from the discharge end of the dumping element that a car emerging from the said element will rest entirely upon the track 43 before coming in contact with the said lever.

In operating the tipple, the rotary dumping element will at all times carry three or more cars, the cars being moved one at a time over the track 48 onto successive platforms of the dumping element as the said element is rotated. Referring more particularly to Fig. 1 of the drawings, the car 18 will be assumed to be empty. A full car is then allowed to move over the track 48 and upon entering the receiving end of

the adjacent platform of the dumping element, will engage the trip 38 associated with the said platform and consequently shift the arms 30 of the bumpers 29 out 5 of the path of the empty car 18. As the full car then advances upon the platform, it will engage the empty car 18 to move it off of the dumping element and onto the track 43. The full car upon passing over 10 the trip 38 will then release the trip when the spring 40 of the stop mechanism associated with the platform, will return the arms 30 of the bumpers to normal position in the path of the loaded car, so that upon 15 moving to engage the said bumpers, the loaded car will then be locked upon the platform by the bumpers and by the coacting brackets of the platform and of the car. The empty car being ejected from the plat- 20 form by the loaded car, will then advance a sufficient distance upon the track 43 to reach the trip 45 and will engage the said trip to release the stops 55 and 56. Upon the release of the said stops, the dumping 25 element will be freed and the weight of the loaded cars thereon will rotate the said element to such position that the full car dis- placing the car 18 will assume the position of the car 19 in which position of the said 30 loaded car, a portion of the coal therein will be dumped into the chute 21.

Attention is now directed to the fact that the dumping element each time it is released will rotate through an arc of 60° assuming 35 that the dumping element is provided with six platforms as illustrated in the drawings. Consequently, the said dumping element cannot attain sufficient momentum to throw the coal from the cars and thus cause it to 40 become broken against the chute 21. In this connection, it will be observed that the chute 21 is arranged close to the dumping element so that the coal will, as the cars are tilted, flow gently from the cars.

45 From the preceding description, it will be seen that as each full car is allowed to advance upon the track 43 to the tipple, my improved mechanism will be automatically operated to release the empty car upon 50 the tipple to be displaced by the full car; to lock the full car in position upon the tipple, and to then release the tipple for rotary movement through an arc of 60° . As this operation is repeated, a full car oc- 55 cupying the position of the car 18 shown in Fig. 1, will first assume the position of the car 19, as previously indicated, when it will be partly dumped and then assume the position of the car 20 when it will be 60 wholly dumped. As the dumping element is then subsequently rotated, the empty cars will be returned to the position of the car 18 to be displaced by full cars.

65 In turning the cars over as the tipple is rotated for effecting the dumping of the

cars, I eliminate the necessity of using car bodies having end gates or other dumping means. Accordingly, the bodies of the cars are each preferably integrally formed so that they will be without seams or cracks. In this way the loss of slack coal or coal dust along the mine tracks, when the cars are in motion, will be eliminated.

It will therefore be seen that I provide a very efficient construction for the purpose set forth. The tipple being automatically operated by cars advanced to position thereon, to effect the dumping of the cars, will have a maximum capacity, while at the same time, owing to the step by step move- 75 ment of the tipple, there will be a minimum breakage of coal. Band brakes 60 surround the annular channel members 10 of the dumping element and are secured to operating levers 61. These levers may be connected in any suitable manner and are operated by an attendant for controlling the rotary movement of the tipple under the weight of loaded cars thereon so that the breaking of coal as it is dumped from the 80 cars will thus be further minimized. These brakes, upon being properly operated, will also prevent the tipple from stopping too suddenly and in so doing will save the stops 55 and 56 from derangement by violent or 85 excessive pounding. Moreover, the brakes being applied by hand will keep the tipple under control while in motion and will compensate for any unequal balance in the load on the tipple.

Having thus described my invention, what I claim and desire to secure by Letters Patent is:

1. A device of the character described including a rotary dumping element, stop mechanism carried thereby for a car upon the said element, stop mechanism for the dumping element, and releasing means for said last mentioned stop mechanism operable by a car moving off of the dumping 105 element and engaging with the said means.

2. A device of the character described including a rotary dumping element, stop mechanism therefor, and means engageable by a series of cars successively discharged 110 from the said element for actuating the said stop mechanism to release the said element by a step by step movement.

3. A device of the character described including a rotary dumping element, stop mechanism therefor, and means engageable by a car discharged from the said element for actuating the stop mechanism to release the said element with the said stop mechanism normally urged to engage the dumping element for arresting said element in its 125 rotary movement at a predetermined point.

4. A device of the character described including a rotary dumping element, stop mechanism normally urged to engage the 130

- said element for arresting the said element in its rotary movement at predetermined points, and means engageable by cars discharged from the said element for actuating the said stop mechanism to release the said element.
5. A device of the character described including a rotary dumping element provided with a platform, stop mechanism carried by the platform and normally urged to active position for engagement with the wheels of a car thereon, means engageable by a car moving onto the platform for shifting the said stop mechanism to inactive position, stop mechanism for the dumping element, and means engageable by a car moving off of the platform for releasing the said last mentioned stop mechanism and freeing the dumping element for rotary movement.
- 10 6. A device of the character described including a rotary dumping element, a stop arranged to engage the said element for arresting the element in its rotary movement at a predetermined point, and a trip associated with the said stop and engageable by a car moving off of the dumping element for actuating the stop to release the said element.
- 15 7. A device of the character described including a rotary dumping element provided with a series of platforms, a stop arranged in the path of the rotary movement of said platforms to selectively engage therewith, and a trip associated with said stop and engageable by a car moving off of one of said platforms for actuating the stop to release the dumping element for rotary movement.
- 20 8. A device of the character described including a rotary dumping element, said element including spaced annular members, and radial spokes supporting each of said members and providing a plurality of platforms upon the said element, stops arranged in the path of the rotary movement of said spokes at opposite ends of the said element, and a trip associated with said stops and operable by a car moving off of one of said platforms for actuating the stops to release the said element for rotary movement, the said stops being arranged to automatically engage each of the platforms successively.
- 25 9. A device of the character described including a rotary dumping element, stops arranged at opposite ends of the said element for arresting the element in its rotary movement, shafts mounted adjacent opposite extremities of said element, lever arms carried by the said shafts, a link connecting certain of said arms, links connecting certain other of said arms with the said stops, and a trip carried by one of said shafts for engagement by a car moving off of the dumping element to actuate the stops for releasing the dumping element for rotary movement.
- 30 10. A device of the character described including a rotary dumping element, stops arranged to engage the said element for holding it against rotary movement, rock shafts arranged adjacent opposite extremities of the dumping element, one of said shafts being provided with upstanding lever arms and the other of said shafts being provided with an upstanding lever arm and with a downwardly extending lever arm, a link connecting one of the lever arms of said first mentioned shaft with the upstanding lever arm of said last mentioned shaft, a link connecting the other lever arm of said first mentioned shaft with one of said stops, a link connecting the downwardly extending lever arm of said last mentioned shaft with the other of said stops, yieldable means associated with said first mentioned link for urging the stops to active position in the path of the rotary dumping element, and a trip carried by said first mentioned shaft and adapted for engagement by a car moving off of the said element for actuating the links against the tension of said yieldable means to release the dumping element for rotary movement.
- 35 11. A device of the character described including a rotary dumping element provided with a platform, rock shafts longitudinally shiftable thereon and provided with bumpers normally arranged in active position, yieldable means associated with the said shafts for normally holding the shafts against longitudinal shifting movement and disposed to resist the impact of the wheels of a car moving onto the platform to engage said bumpers, means operatively connected to the shafts and engageable by a car for moving the bumpers to inactive position, and stop mechanism engageable by a car moving off of the platform for releasing the dumping element.
- 40 12. A device of the character described including a rotary dumping element provided with a platform, longitudinally shiftable rock shafts carried by the platform, bumpers mounted upon said shafts and normally arranged in active position with the said shafts adapted for movement longitudinally to take up the impact of the wheels of a car moving onto the platform to engage said bumpers, links swingingly connected to said bumpers, a rod pivotally connected to said links, yieldable means associated with said rod for normally urging the bumpers in active position, a trip lever pivotally connected to the said rod and adapted for engagement by a car moving onto the platform to shift the bumpers to inactive position, and stop mechanism engageable by a car moving off of the platform for releasing the dumping element.
- 45 13. A device of the character described including a rotary dumping element, stop mechanism carried thereby and normally

urged to active position for engagement with a car upon the dumping element, a trip lever associated with said stop mechanism and engageable by a car moving onto the dumping element for shifting the said mechanism to inactive position, stop mechanism for the dumping element, and a trip lever engage-

able by a car moving off of the dumping element for releasing the said last mentioned stop mechanism and freeing the dumping 10 element for rotary movement.

In testimony whereof I affix my signature.

THOMAS J. WILLIAMS. [L. S.]
